UNITED STATES PATENT OFFICE.

ALBERT B. FRENIER, OF DAVENPORT, IOWA.

CORN-PLANTER.

SPECIFICATION forming part of Letters Patent No. 732,687, dated June 30, 1903.

Application filed September 6, 1902. Serial No. 122,311. (No model.)

To all whom it may concern:

Be it known that I, ALBERT B. FRENIER, a citizen of the United States of America, and a resident of Davenport, Scott county, Iowa, have invented a certain new and useful Improvement in Corn-Planters, of which the following is a specification.

My invention relates to corn-planters in general, but more particularly to planters of the check-row type, and especially to those in which the forward runner-frame has a pivotal or swinging connection with the rear wheel-frame.

Generally stated, the object of my invention is to provide an improved arrangement for connecting the runner-frame with the wheel-frame.

A special object is to provide a construction whereby the box-rail of the runner-frame may also serve as an axle for the ground-wheels.

It is also an object to provide certain details and features of improvement tending to increase the general efficiency of a corn-planter of this character.

To the foregoing and other useful ends my invention consists in matters hereinafter set forth and claimed.

In the accompanying drawings, Figure 1 is a plan of the corn-planter involving the principles of my invention. Fig. 2 is a section on line 2 2 in Fig. 1. Fig. 3 is a detail section on line 3 3 in Fig. 2.

The forward runner-frame A can be of any suitable construction. This frame can be provided with the usual runners or furrow-openers a and also with the hoppers or seed-boxes a' . It will be understood that the dropping mechanism, which is not shown or described, and also the check-rowing devices can be of any suitable known or approved construction. The usual tongue a^2 can be secured to the said runner-frame. As a matter of special improvement, however, the transversely-extending rotary member B of the said runner-frame is preferably cylindric and connected with the boxes and runners by means of bearings b . This rear portion of the runner-frame is ordinarily known as the "box-rail," and heretofore has been rigidly connected with the balance of the runner-

frame structure—that is to say, has not been mounted for rotation and is served merely as a strengthening portion of the runner-frame; but, as stated, with my improved construction and with a view to simplifying the organization and method of connecting the front and rear frames the said box-rail is mounted so as to also serve as a crank-axle for the ground-wheels C. Preferably these wheels are mounted on the crank-arms b' , which may either be integral with the said combined axle and box-rail or which may be secured to the latter in any suitable manner. In this way the member B has a double function, as it forms a part of both the runner-frame and the wheel-frame, thus reducing the weight and number of parts and at the same time insuring more than the usual degree of strength and rigidity.

The arrangement for raising and lowering the runner-frame can be of any suitable character. For example, the crank-arms b' can be connected by an arch D, adapted to support the seat-bars d , which latter are pivotally connected at their forward ends with the tongue a^2 . The driver's seat E, positioned, as shown, upon the rear ends of these bars, permits the driver's weight to be utilized for counterbalancing the runner-frame. A hand-lever F, having an arm f connected with the rear end of the tongue by means of a rod or bolt f' , can be pivoted between the seat-bars and arranged in position to be readily grasped by the driver. A rack f^2 can be secured to one of the seat-bars, and the lever can be provided with the usual catch or locking device adapted to engage said rack. In this way the driver can raise the runners from the ground by grasping and pulling back the said lever. When the lever is thus manipulated, the combined axle and box-rail B turns freely in its bearings, allowing the wheel-frame to swing relatively to the runner-frame. Even when the lever is locked, as shown in Fig. 2, the two frames are preferably capable of a slight relative movement, so as to allow the runners to rise over stones without breaking any of the parts. This can be accomplished by placing a spring on the rod f' between the rear end of the tongue and the lever-arm f . Thus it will be seen that I pro-

vide a construction which permits a part of the runner-frame to be utilized as a part of the wheel-frame.

The planter thus constructed is very light and strong and at the same time very rigid. Furthermore, the parts, which are comparatively few in number, can be readily assembled and can be easily taken apart.

What I claim as my invention is—

- 10 1. A planting-machine comprising a runner-frame and a pair of ground-wheels connected by a combined axle and box-rail.
- 15 2. A planting-machine comprising a runner-frame provided with a rotary box-rail, a pair of crank-arms on said rail, and a pair of ground-wheels on said arms.
- 20 3. A planting-machine comprising a runner-frame provided with a rotary rear bar, a pair of crank-arms on said bar, and a pair of ground-wheels on said arms.
- 25 4. A planting-machine comprising a runner-frame having a rotary box-rail, a pair of crank-arms secured rigidly upon said rail, and a pair of ground-wheels on said arms.
- 30 5. A planting-machine comprising an axle, a pair of crank-arms on said axle, a runner-frame having axle-bearings located outside of said arms, and a pair of ground-wheels on said arms.
- 30 6. A planting-machine comprising a run-

ner-frame provided with a combined axle and box-rail, a pair of crank-arms on said rail, a pair of ground-wheels on said arms, an arch connecting said arms, a tongue extending forward from the runner-frame, seat-bars connecting said arch with said tongue, a seat on said bars, and a lever pivoted to the seat-bars and connected with the said tongue.

35 7. A planting-machine comprising a pair of runners, a pair of ground-wheels and a combined axle and box-rail and a pair of seat-bars serving as medium of connection between said wheels and runners.

40 8. A corn-planter comprising a pair of runners, a pair of ground-wheels, a combined axle and box-rail, a pair of crank-arms, on said axle, the ground-wheels being mounted on said arms, a tongue, a pair of seat-bars connecting the tongue with said arms and a lever for raising and lowering the said runners.

45 9. In a planting-machine, the combination of runners, ground-wheels, seedboxes, and a combined axle and box-rail.

50 Signed by me at Davenport, Scott county, Iowa, this 26th day of August, 1902.

ALBERT B. FRENIER.
